US00D870067S

(12) **United States Design Patent** (10) **Patent No.:** **US D870,067 S**
Hu (45) **Date of Patent:** **** Dec. 17, 2019**

(54) **WIRELESS HEADSET**

(71) Applicant: **SHENZHEN QIANHAI PATUOXUN NETWORK AND TECHNOLOGY CO., LTD**, Shenzhen (CN)

(72) Inventor: **Zaihui Hu**, Shenzhen (CN)

(73) Assignee: **SHENZHEN QIANHAI PATUOXUN NETWORK AND TECHNOLOGY CO., LTD**, Shenzhen (CN)

(**) Term: **15 Years**

(21) Appl. No.: **29/703,675**

(22) Filed: **Aug. 29, 2019**

(51) LOC (12) Cl. **14-01**

(52) U.S. Cl.

USPC **D14/205**

(58) **Field of Classification Search**

USPC D14/205, 223, 372; 181/129, 130, 135; 379/430, 431; 381/380, 381, 374; 455/90.3, 575.1, 569.1

Primary Examiner — Paula Allen Greene

(57) **CLAIM**

The ornamental design for a wireless headset, as shown and described.

DESCRIPTION

FIG. 1 is a perspective view of a wireless headset showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a perspective view of the wireless headset where earphones are accommodated in corresponding grooves of the wireless headset;

FIG. 10 is an enlarged view of portion 10 shown in FIG. 1; and,

FIG. 11 is an enlarged view of portion 11 shown in FIG. 1. The broken lines in the drawings depict portions of the wireless headset that form no part of the claimed design.

1 Claim, 11 Drawing Sheets
